CATHODES FOR ELECTRON TUBES

Helmut Langer, Stamford, Conn., assignor to The Machlett Laboratories, Incorporated, Springdale, Conn., a corporation of Connecticut

Filed Mar. 25, 1960, Ser. No. 17,666
8 Claims. (Cl. 313—270)

This invention relates to electron discharge devices and has particular reference to novel indirectly heated cathodes capable of reaching operating temperatures in a relatively short time.

In the operation of electric discharge devices, and particularly electron tubes for high frequency and ultra-high frequency applications, one serious problem is the lengthy warm-up time required to heat the cathode to a temperature suitable for efficient operation. Conventional tubes employing indirectly heated planar cathodes usually require 40 to 60 seconds warm-up time before the tube can be operated efficiently.

The tube of the present invention is provided with a novel cathode structure which is so constructed and arranged as to provide more efficient concentration of heat at the emissive portion of the cathode and throughout a relatively expansive area thereof, whereby preoperative warm-up time is reduced to about 10-12 seconds.

It is, accordingly, a primary object of this invention to provide an electron tube with a novel cathode structure which permits efficient operation of the tube after relatively short warm-up periods.

Another object is the provision of a novel cathode structure embodying planar emitter and heater elements so constructed, arranged and shielded as to concentrate heat in the area of the emitter and throughout a relatively expansive area thereof.

Another object is to provide a cathode structure of the above character which includes a novel baffle structure embodying gettering means located in the areas of the tube which acquire most elevated temperatures.

A further object is to provide a cathode structure of the above character which is simple in construction, efficient in operation and relatively inexpensive to manufacture.

Other objects will become apparent from the following description taken in connection with the accompanying drawing, in which

FIG. 1 is an axial sectional view of a cathode structure embodying this invention;

FIG. 2 is a transverse sectional view taken substantially on line 2—2 of FIG. 1 looking in the direction of the arrows; and

FIG. 3 is a transverse sectional view taken substantially on line 3—3 of FIG. 1 looking in the direction of the arrows.

Referring more particularly to the drawing, the structure shown in FIG. 1 comprises a substantially planar emitter 10 having a downwardly turned peripheral flange 11 by which the emitter is fixed to one end of a tubular support foil 12. The other end of support 12 is mounted on one end of a substantially tubular cathode supporting ring 13 which is in turn sealed at its opposite end by a glass ring 14 to a tubular inner terminal 15. One end of an outer terminal 16 is sealed directly to the cathode supporting ring 13.

Adjacent the inner surface of the emitter and in predetermined closely spaced relation thereto is a coiled heater 9 of the flat "pancake" type having one end formed as a leg 17 which is connected by metal connector 18 to supporting ring 13. Thus, the outer terminal 16, supporting ring 13, connector 18 and leg 17 form one side of an electrical circuit to the heater 9.

2

The other end of the heater coil forms a leg 19 which extends into one end of a length of metal tubing 20 and into a metal sleeve 21 located within tubing 20. In assembling a heater 9 with the sleeve 21 and tubing 20, the parts are initially assembled in desired relation, with the lower end of sleeve 21 being located at a predetermined known distance from the lower end of tubing 20. With the sleeve in this position and with the heater 9 spaced a proper distance from the adjacent end of tubing 20, pressure is applied to the tubing in an area overlying sleeve 21 and leg 19. Such pressure may be applied mechanically to cause constriction of the tubing and of the sleeve, so as to hold the leg firmly and immovably in position. In this way the heater 9 becomes fixed at a predetermined known distance from the tubing 20.

After the heater unit is assembled, tubing 20 is mounted over an elongated axially extending member or pin 22 and retained in position as by spot welding. Pin 22 is fixed at its lower end to a disc 23 which extends transversely of and closes inner terminal 15. The spacing between the end of pin 22 and the emitter 10 is a predetermined value. Thus, the engagement of sleeve 21 with pin 22 automatically determines the spacing of the heater 9 from emitter 10. Terminal 15, disc 23, pin 22, tubing 20, sleeve 21, and leg 19 complete the other side of the circuit to the heater 9.

The emitter 10 is preferably a thin sheet of nickel alloy located about ".005" from the heater 9 and having an oxide coated surface for copious electron emission when heated. The heater coils and portions of legs 17 and 19 are preferably coated with aluminum oxide so that the turns of the coil may be closely wound and may actually engage one another without shorting.

To avoid shorting of the heater 9 with emitter 10 under thermal expansion stresses, both are preferably bowed to a predetermined concavity as shown. Thus, they will remain substantially parallel to each other during operation of the tube. Such concavity of the emitter also causes expansion in a direction toward the heater rather than toward a grid with which the cathode may be used.

It is particularly pointed out that a so-called "planar" heater of this character can be made to cover substantially the entire inner surface of the emitter, thus providing greater heating efficiency than is possible with known conventional devices which employ a relatively heavy emitter having on one side a centrally disposed tubular extension within which is located a spring-like heater coil, only one end of which actually lies adjacent the emitter. In the present structure the entire emitter is efficiently and relatively uniformly heated.

Additionally, means is provided in the present structure for efficiently concentrating heat in the area of the emitter. Such means comprises a group of spaced transversely extending disc-like baffles 24, 25 and 26 which are mounted on the end of the tubing 20 adjacent the heater 9. The tubing 20 is provided with a circumferential flange or rim 27 which may be drawn out of the material of the tubing or may be attached to the tubing a short distance from the end. Flange 27 provides a seat against which are located the group of baffles together with small annular spacers 28 between the baffles. The extreme end of the tubing 20 is flared over as shown at 29 in FIG. 1 to retain the baffle assembly in place.

The baffles are of a diameter nearly approaching the diameter of the heater 9 and thus by reflection efficiently confine heat to the area of the emitter.

The baffle structure possesses additional novelty in that one of the discs, preferably middle disc 25, is made of titanium or other selected gettering material. Since this disc is located in one of the hottest areas of the cathode,

it will function as a getter at elevated temperatures which other areas of the structure will not reach.

An additional getter for functioning at lower temperatures is provided by a short length 30 of barium or the like which is affixed to the inner side of foil 12 where it may operate at a predetermined time and temperature by radiation from the heater-baffle assembly.

It will be apparent from the foregoing that an improved cathode structure for an electron tube has been provided which, by more efficient heating of the cathode emitter and concentration of heat at the emitter and by the particular construction and arrangements of the elements accomplishing these improvements, permits the tube to be efficiently operated with relatively short warm-up times.

It is to be understood that modifications may be made in the structures shown and described without departing from the spirit of the invention as expressed in the accompanying claims.

I claim:

1. A quick heating cathode structure for electron tubes, comprising a terminal structure including a pair of hollow cylindrical terminals located in spaced relation one within the other, a tubular support mounted at one end on the terminal structure in conductive relation with the outer terminal, a sealing member within the inner terminal, an axially extending pin fixed at one end to the sealing member, a disc-like emitter secured at its periphery to the opposite end of the support, a flat coiled heater closely adjacent the inner side of the emitter and substantially parallel thereto, baffle means disposed adjacent the opposite side of the heater, and a tubular member carrying the baffle means and mounted on said pin, one end of the heater being connected to said tubular member and the other end being connected to the outer terminal.

2. A cathode structure substantially as set forth in claim 1 wherein the tubular member has a circumferential flange spaced from its end nearest the heater and against which one side of the baffle means resides, and further has means on its extreme end engaging the opposite side of the baffle means for retaining the baffle means in position.

3. A cathode structure substantially as set forth in claim 1 wherein the tubular member contains a sleeve, the adjacent end of the heater is located within the sleeve, and means is provided for rigidly securing the end of the heater, the sleeve, and the tubular member in assembled relation.

4. A cathode structure substantially as set forth in claim 3 wherein said means comprises pressure-induced constrictions in the tubular member and sleeve whereby the assembled parts are frictionally retained in assembled relation.

5. A quick-heating cathode structure for electron tubes, comprising a terminal structure including a pair of hollow cylindrical terminals located in spaced relation one within the other, a tubular support mounted at one end on the terminal structure in conductive relation with the outer terminal, a disc-like emitter secured at its periphery to the opposite end of the tubular support, a sealing member within the inner terminal, an axially extending pin fixed at one end to the sealing member and having its opposite end terminating at a predetermined distance from the emitter, a tubular member mounted upon the pin and containing therein a fixedly located sleeve, a heater located adjacent the emitter and having one end fixed to said sleeve, one end of the sleeve abutting the end of the pin, the spacing between the heater and the abutting end of the sleeve being predetermined whereby when the heater, sleeve and tubular member are assembled as a unit on the pin the heater will be positioned at a predetermined distance from the emitter.

6. A cathode structure for electron tubes, comprising a pair of hollow cylindrical terminals located in spaced relation one within the other, a cylindrical support mounted at one end on the outer terminal, a sealing member within the inner terminal, sealing means between the terminals and insulating one from the other, a disc-like emitter secured to the opposite end of the cylindrical support, a heater adjacent the inner side of the emitter, an elongated member connected at one end to the sealing member and extending axially a predetermined distance toward the emitter, a tubular member telescoped upon and fixed to the elongated member, and means within the tubular member for limiting the extent to which the tubular member is telescoped onto the elongated member, said means supporting one end of the heater.

7. A cathode structure substantially as set forth in claim 1 wherein the baffle means comprises a group of spaced discs extending transversely of the structure, one of the discs being formed at least in part of a gettering material.

8. A cathode structure substantially as set forth in claim 1 wherein the baffle means comprises three spaced discs, the middle disc being formed of titanium.
